(57) **CLAIM**

The ornamental design for a underwater booster as shown and described.

DESCRIPTION

FIG. 1 is a front, right perspective view of the underwater booster;

FIG. 2 is a rear, left perspective view thereof;

FIG. 3 is a bottom, left view perspective thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof;

FIG. 10 is a partially enlarged view of FIG. 1; and,

FIG. 11 is a partially enlarged view of FIG. 3.

In the figures, broken lines depict portions of the underwater booster that form no part of the claimed design. In FIGS. 1, 3, 10 and 11, the dash-dot-dash broken lines encircling portions of the claimed design are illustrated in an enlargement view and form no part of the claimed design.

1 Claim, 11 Drawing Sheets
